Patented Dec. 31, 1968

213,063

SPOT LAMP

Joseph Thornley and Frank Stanley Allwork, Thetford,
Norfolk, England, assignors to Mole-Richardson (England) Limited, London, England, a British company

Filed May 3, 1967, Ser. No. 6,930

Claims priority, application Great Britain Feb. 7, 1967

Term of patent 14 years

(Cl. D48—20)

FIG. 1.

Des. 213,063

PAGE 2

FIG. 2.

FIG. 3.

Des. 213,063

PAGE 4

FIG. 4.

FIG. 5.

FIG. 6.

FIGURE 1 is a front view of a spot lamp, showing our new design;

FIGURE 2 is a rear view thereof;

FIGURE 3 is a top plan view thereof;

FIGURE 4 is a bottom plan view thereof;

FIGURE 5 is a left side elevational view thereof; and FIGURE 6 is a right side elevational view thereof.

The small circular holes throughout the disclosure are representative of perforated material, said perforated pattern being understood to be continuous throughout the areas so shaded and so shown for convenience of illustration.

We claim:

The ornamental design for a spot lamp, as shown and described.
